UNITED STATES PATENT OFFICE.

RAY H. FITZ GERALD, OF PITTSBURGH, PENNSYLVANIA.

DISPENSING AND DISPLAYING CARTON.

1,378,533.

Specification of Letters Patent. Patented May 17, 1921.

Application filed June 23, 1919. Serial No. 306,196.

To all whom it may concern:

Be it known that I, RAY H. FITZ GERALD, a citizen of the United States, and a resident of Pittsburgh, in the county of Allegheny and State of Pennsylvania, have invented certain new and useful Improvements in Dispensing and Displaying Cartons; and I do hereby declare the following to be a full, clear, and exact description 10 of the invention, such as will enable others skilled in the art to which it appertains to make and use the same.

This invention relates to improvements in dispensing and display cartons and more 15 particularly to such as are made of paper or card board—one object of the invention being to provide a carton for dispensing cylindrical articles and to so construct the device that the major bulk of the articles 20 will be held back from the discharge outlet and to provide the carton with a simple and efficient tray construction to receive the articles passing out through the discharge opening and thus facilitate the delivery 25 of the articles to the customer.

With this and other objects in view the invention consists in certain novel features of construction and combinations of parts as hereinafter set forth and pointed out in 30 the claims.

In the accompanying drawings; Figure 1 is a perspective view of a carton, partly broken away, showing an embodiment of my invention; Fig. 2 is a view of the blank; 35 Fig. 3 is a view of the blank from which the tray is made; Fig. 3^a is a view of the tray; Fig. 4 is a view of the blank from which the lining member and inclined bottom platform member are made; Fig. 4^a 40 is a view of the combined lining and bottom platform member, and Fig. 5 is a sectional view showing the manner in which the discharge opening of the carton may be closed.

The body 1 of the carton is made rectangular in form, from a blank comprising front and back members 2, 3, and side members 4, 5. The side members 4, 5 are provided at their upper ends with flaps 6, 6 to be folded inwardly and the back member 50 3 is made at its upper end with a flap 7 to overlie the flaps 6, 6 and thus the top of the body of the carton is formed. The flap 7 may be made with a gluing flange 8, which may be tucked in behind panel 2 as 55 indicated in Fig. 1. The bottom of the car-

ton is formed by flaps 9, 9 at the lower ends of the sides 4, 5, and a flap 10 at the lower end of the back member 3. A flap 11 may be provided at the upper end of the front member 2 and this flap may have advertising matter thereon. The lower portion of the front member 2 is cut away to form an elongated discharge opening 12.

A shell or lining 13 is located within the body of the carton and comprises a back 60 member 14 and side members 15-15 as shown in Figs. 4 and 4^a, the front of said lining member being open. The back member 14 is provided with a member 16 extending from the line 17 (Fig. 4) and severed 65 from the side members 15. The member 16 is notched at 18 and provided at its free end with tongues 19. The member 16 is bent forwardly on the line 17 to provide an inclined platform 20 extending forwardly 70 and downwardly from the back member 14 to the front of the carton at the bottom of the discharge opening 12. The member 16 is bent backwardly on the line 21, Fig. 4 and made to project under the inclined 75 bottom platform and is also bent upwardly on the line 22 and the tongues 19 caused to pass through the notches 18 and project above the face of the inclined bottom platform.

The inclined platform of the bottom member will tend to cause the cylindrical articles within the carton to move forwardly, but the upstanding tongues will act as baffles to hold back the major bulk 90 of the articles, permitting only the front vertical tier of articles to be disposed in a vertical plane in front of that of said tongues. When an article passes through the discharge opening 12, the next article 95 in the front tier will drop into position and an article will move from the top of the next tier to the top of the front tier of articles, and this will continue, as articles pass one after another through the discharge opening, until only two articles remain on the bottom inclined platform. These last two articles will be held back by the tongues 19, and the merchant may cause them to pass over said tongues by 100 jarring or shaking the carton.

When an article passes through the discharge opening 12, it will become deposited into a tray 23, (with which the carton is provided) where it will be exposed to view 110

and from which it can be readily grasped by the purchaser. The article within the tray will serve to hold back the article in line with the discharge opening, and when an 5 article is removed from the tray, the next article will take its place and another article in the first tier will descend and assume a position in line with the discharge opening. The tray 23 is made from a separate 10 blank such as shown in Fig. 3 and is disposed upon an extension 24 of the bottom member 10 at the lower end of the back 3 of the carton and the end flaps 9 of the sides 4, 5 of the carton are provided with tongues 15 25 which underlie the bottom of said tray so as to be disposed between the latter and the extension 24. The tray 23 comprises a bottom 26 provided at its ends with end members 27, the latter being made with upwardly projecting lugs or extensions 28. The front wall 29 of the tray is formed by folding portions of an extension 30 upon themselves and the end members 27 are provided with tongues 31 which enter between 25 the folds of the front wall 29 of the tray. The extension 30 is made with a flange 32 which overlies the bottom 26 and said extension 30 is also made with a hole 33 to provide a notch 33^a when said extension has 30 been folded to form the front wall 29 of the tray.

The ends 27 of the tray enter between the sides of the body of the carton and the sides of the inserted lining and the lugs 28 on 35 said ends of the tray project above the upper edge of the discharge opening 12 so that they may engage the front 2 of the carton and thus hold the tray in proper position. The tray may be moved inwardly until its 40 front is even with the front of the carton and then the bottom extension 24 may be folded upwardly and its free edge portion 24^a inserted through the opening 12 and permitted to rest against the inner face of 45 the front of the carton,—thus closing the discharge opening. When the tray is slid into the body of the carton, the bottom of said tray will move under the inclined platform 20 and the ends 27 will slide between 50 the lining member and the sides of the carton.

Various changes might be made in the details of construction of my invention without departing from the spirit thereof or 55 limiting its scope and hence I do not wish to restrict myself to the precise details herein set forth.

Having fully described my invention, what

I claim as new and desire to secure by Letters-Patent, is:—

60

1. The combination with the body of a carton having a discharge opening, of a tray communicating with said discharge opening, an inclined bottom platform, and baffle tongues projecting upwardly from 65 said inclined bottom platform rearwardly of said discharge opening.

2. The combination with the body portion of a carton, of a separate lining member within said body portion and having a front 70 opening, an inclined bottom integral with said lining member and having a part provided with tongues projecting upwardly from said inclined bottom within said lining.

3. The combination with the body of a carton having a discharge opening, of a lining member comprising a back and sides, the back of said lining member having an extension forming an inclined bottom for 80 the carton, said extension having an integral part provided with tongues passing through and projecting above the upper face of the inclined bottom platform rearwardly from the discharge opening of the 85 carton.

4. A display carton comprising a body portion having a discharge opening and an extension projecting forwardly from its bottom, a tray mounted upon said extension 90 in front of said discharge opening and connected with the body of the carton, said body portion having flaps overlying said forward extension of the bottom, and a lining member disposed in said body portion 95 forming an inclined bottom platform and tongues projecting through and above the upper face of said platform rearwardly of the discharge opening of the carton.

5. The combination with the body portion 100 of a carton having a discharge opening and a bottom extension below said opening, of a tray mounted on said bottom extension, said tray made from a single blank and comprising a bottom, a folded front, end members connected with the body of the carton, and tongues projecting from the end members and entering between the folds of the front 105 of the tray.

In testimony whereof I have signed this 110 specification in the presence of two subscribing witnesses.

RAY H. FITZ GERALD.
